UNITED STATES PATENT OFFICE.

MORTON C. HUTCHINSON, OF WOODBURY, NEW JERSEY.

BOILER-RETARDER MACHINE.

1,263,896.

Specification of Letters Patent. Patented Apr. 23, 1918.

Application filed October 5, 1916. Serial No. 123,812.

To all whom it may concern:

Be it known that I, MORTON C. HUTCHINSON, a citizen of the United States, residing at Woodbury, in the county of Gloucester, State of New Jersey, have invented a new and useful Boiler-Retarder Machine, of which the following is a specification.

My present invention comprehends a novel construction of machine which while 10 specially designed for the production of retarder strips such as are used in boiler tubes, is not limited to such use and may be employed in all cases wherein it is desired to form a bend at different points in 15 the length of a strip of material.

Another object of my invention is to devise a novel mounting for a plurality of sets of rolls, one set of which is rotatably adjustable with respect to the other set and 20 novel means for locking the parts in their adjusted position.

Other novel features of construction and advantage will hereinafter more clearly appear in the detailed description of my invention.

For the purpose of illustrating my invention, I have shown in the accompanying drawings a preferred embodiment of it which is typical of the invention and which 30 will give satisfactory and reliable results in practice. It is, however, to be understood that this embodiment is typical only and that the various instrumentalities of which my invention consists can be variously arranged and organized and that my invention is not limited to the precise organization of these instrumentalities as herein shown and described.

Figure 1 represents a top plan view of 40 a boiler retarding machine embodying my invention.

Fig. 2 represents a front elevation of the machine.

Fig. 3 represents a sectional view, the 45 section being taken in the plane indicated by the line 3-3 of Fig. 2.

Fig. 4 represents a sectional view, in the same plane as Fig. 3 after the rotatable portion has been given one-quarter of a revolution.

Similar numerals of reference indicate corresponding parts.

Referring to the drawings:

1 designates the base plate of a boiler retarder machine embodying my invention, said base plate being provided with an aper-

ture 2 in order that it may be clamped to a table or other support. Rising from the base plate 1 is a standard or head 3 having an opening 4 therethrough preferably centrally located, and in this opening are journaled the superposed rollers 5, it being understood that any desired type of journal may be employed.

The standard 3 since it is carried by the 65 stationary base plate 1, is stationary and is provided with a desired number of curved slots 6, two of such slots being employed in the present instance. The front face of the standard 3 is recessed as at 7, thereby 70 forming the annular bearing 8.

9 designates a rotatable head having the threaded apertures 10 and 11, two sets of which are shown in the present instance. 12 designates bolts or cap screws which pass 75 through the slots 6 and engage the apertures 10 to provide for a right-hand rotation of the head 9, and in case a left-hand rotation of the head 9 is desired, these cap screws engage the threaded apertures 11 instead of 80 the apertures 10. The rear face of the head 9 is recessed or chambered as at 13 and is provided with a laterally extending annular flange 14 which engages the bearing 8 when the parts are assembled.

15 designates the wall of an opening through the head 9, the opening communicating with the chamber or recess 13, and in said opening 15 are disposed the second set of superposed rolls 16. The periphery 90 of the rotatable head 9 is provided with a desired number of apertures 17 into which a working tool is adapted to be inserted to effect the desired adjustment of the rotatable head 9.

The adjoining outer faces of the standard 3 and the rotatable head 9 are calibrated or provided with insignia indicative of the amount of rotation which has been imparted to the rotatable head.

In the drawings I have shown one manner of doing this by forming a line or depression 18 on the stationary standard 3 and by forming in proximity to the apertures 17 the lines 19, which may be brought into register with the line 18 on the partial rotation of the head 9. Each roll, if desired, may be recessed intermediate its ends to form a neck 20 and the heads 21, as will be understood by reference to Figs. 2 and 4.

22 designates a swivel of any desired type and which in the form illustrated consists

of a hook 23, 24 adapted to engage an aperture in a strip of material 25. 26 designates a swivel block through which the shank of the hook 23 passes, and an anti-friction bearing 27 is provided which bears against the swivel block. The shank of the hook is provided with nuts 28 one of which serves as a lock nut.

29 designates a yoke pivotally connected 10 with the swivel block 26 and designed to be actuated either manually or mechanically in accordance with the conditions met with in practice.

The operation of my novel boiler retarder 15 machine will now be apparent to those skilled in this art, and is as follows:—

The bed plate 1 is first clamped into position and the strip of material 25 to be twisted about its axis is inserted in position through 20 the space between the alining rollers 5, 5 and 16, 16, as seen in Fig. 3. The hook 23 of the swivel being connected to the strip, the same can be readily advanced either manually or mechanically by any suitable 25 means, and after the strip has been drawn a short distance to the left of the position seen in Fig. 3, the operator inserts a suitable implement in the hole 17 and turns the head 9 to the desired extent until the rollers 16 30 are disposed at right angles to the rollers 5 substantially as seen in Fig. 4, whereupon the bolts 12 are tightened. When the head 9 is turned as stated, the twist shown of the strip 25 at the left of the head 9 in Fig. 4 is formed; the said twist being made in the 35 chamber 13 and by virtue of the rollers 16 being moved from the position shown in Fig. 3 to that shown in Fig. 4. Then as the strip 25 is drawn farther toward the left 40 and its portion at the left of the rollers 16 turns about its axis, the twist referred to will pass, in upright position, between the rollers 16, and then as the portion of the strip 25 at the left of the rollers 16 further 45 turns about its axis, the succeeding portion of the strip will pass between the rollers 16 and will be followed by the twisted portion shown in the chamber 13, Fig. 4, and so on until the desired length of retarder is 50 produced.

It will be understood that the strips produced by my novel machine are what are commonly termed "retarder strips" and which are longitudinally disposed in the flues 55 of steam boilers for the purpose of retarding the passage of the hot gases or products of combustion therethrough, so that it will be apparent that while a high degree of accuracy in the bends or twists of the retarders is not essential, my novel machine will produce the same with a substantial uniform spiral or helical contour, so that the same will be sufficiently accurate for the purposes intended.

65 It will be understood that while I have

described my novel mechanism as being adapted particularly for the production of these retarder strips used in steam boiler flues, the same may be employed for producing twisted or helical strips for augers 70 or for twisting bars or strips to form binders for cement structures and other purposes, and may be employed for twisting cold metallic resilient and galvanized strips, as fencing strips, or for auger bits for coal 75 or rock drilling machinery, or it may be used for twisting metal to form spiral conveyers or to form twisted or helical strips adapted for any other uses than those above mentioned.

80 My invention is particularly adapted for use in machine shops or on shipboard where a light and portable machine of this character is desired, since the machine can be readily transported to any desired point 85 and after being used to the desired extent can be readily removed and transported to any other place where it is desired to use the same.

85 It will be apparent that the machine can be 90 readily taken apart when desired and in case of any injury to the rollers 16 or 5, the same can be readily replaced by unskilled labor.

Having thus described my invention, 95 what I claim as new and desire to secure by Letters Patent, is:—

1. In a device of the character described, the combination of a stationary head having an aperture and a wall surrounding the aperture and extending rearwardly from the 100 head and also having a recess in its front face, in communication with said aperture, a head rotatably adjustable on said stationary head and having an aperture and a wall surrounding said aperture and extending 105 forwardly from the head and also having a recess in its rear face, in communication with the recess of the stationary head, rolls mounted in the rearwardly extending wall of the stationary head, and rolls mounted 110 in the forwardly extending wall of the rotatably adjustable head.

2. In a device of the character described, the combination of a stationary head having an aperture and a wall surrounding the 115 aperture and extending rearwardly from the head and also having a recess in its front face, in communication with said aperture, and slots that describe parts of a circle, a head rotatably adjustable on said 120 stationary head and having an aperture and a wall surrounding said aperture and extending forwardly from the head and also having a recess in its rear face, in communication with the recess of the stationary head, 125 and further having threaded sockets in its rear face and in registration with the slots of the stationary head, threaded bolts extending through said slots and into said threaded sockets, rolls mounted in the rear- 130

wardly extending wall of the stationary head, and rolls mounted in the forwardly extending wall of the rotatably adjustable head.

5 3. In a device of the character described, the combination of a stationary head and a head rotatably adjustable on the stationary head; the said heads having apertures and

pairs of rolls therein and also having recesses in their opposed faces in communication with each other and said apertures.

MORTON C. HUTCHINSON.
